UNITED STATES PATENT OFFICE

KARL M. HAMILTON, OF DAVENPORT, IOWA, ASSIGNEE TO AMERICAN CAR AND FOUNDRY COMPANY, OF ST. LOUIS, MISSOURI, A CORPORATION OF NEW JERSEY.

BOLSTER.

1,109,629.

Specification of Letters Patent.

Patented Sept. 1, 1914.

Application filed July 1, 1913. Serial No. 776,865.

To all whom it may concern:

Be it known that I, KARL M. HAMILTON, residing at Davenport, Scott county, Iowa, and being a citizen of the United States, have invented certain new and useful Improvements in Bolsters, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a plan view of the bolster assembled with the underframe of the car. A portion of the center sill cover plate is broken away at the bolster to show the relative position of the several parts. Fig. 2 is an elevation of the assembled bolster in position. Fig. 3 is a sectional view, the section being taken on line 3—3 of Fig. 2, looking in the direction indicated by the arrow. Fig. 4 is a horizontal section taken on line 4—4 of Fig. 2, and shows the engaging parts of the bolster in operative relation. Fig. 5 is a vertical section on line 5—5 of Fig. 2 showing the lapping bolster extensions and bolster filler jaws secured in position. Fig. 6 is a detail plan view of the extensions of the bolster side sections, which are adapted to be lapped and riveted as shown in Figs. 2, 4 and 5. Fig. 7 is an elevation thereof. Figs. 8, 9 and 10 show respectively the plan, side elevation and end views of the bolster filler casting forming the center section of the bolster. Fig. 11 is a side elevational view of a modification. Fig. 12 is a section of the modification taken on line 12—12 of Fig. 11. Fig. 13 is a horizontal sectional view, the section being taken on line 13—13 of Fig. 11. Fig. 14 is a sectional view looking toward the center sill, the section being taken on line 14—14 of Fig. 11. Figs. 11, 12, 13 and 14 illustrate one modification of the invention in which the positions of the engaging parts are reversed, that is to say, instead of the upwardly projecting extension on the bolster filler embracing the side section extensions as shown in corresponding Figs. 2, 5, 4 and 3, the side

section extensions embrace the single upwardly extending flange on the bolster filler. Fig. 15 is a fragmentary plan view of a further modification in which side sections A—B are provided with extensions 1 having flanges 2^a widened to accommodate a cover plate 28 secured thereto by rivets 29, designed to reinforce the connection of the bolster parts between the sills. Fig. 16 is an end view of the modification of Fig. 15. Fig. 17 is a sectional view, the section being taken on line 17—17 of Fig. 16. Fig. 18 illustrates a method of reinforcing the side and center section connection by extending flanges 2 of the side section extensions 1 and flanges 12 of the center section jaws 9 and securing said flanges together by rivets 30. Fig. 19 is a view similar to Fig. 18 with the cover plate of Figs. 15—17 inclusive and the flanges, etc., of Fig. 18 combined in one structure.

The object of the invention is to provide first, a sectional bolster in which all of the parts may be readily assembled to form a bolster structure complete in itself as an article of manufacture, and which is also capable of being assembled with the underframe of a car as shown in the drawings; second, to so connect the parts of the bolster as to develop in a simple and efficient manner the full strength of the engaging parts so that the bolster will perform its full function as a supporting member independently of its association with other members of a car underframe in which it may be used.

Referring more particularly to the drawings, A and B are bolster sections of cast metal arranged on opposite sides of spaced channel-shaped center sills and provided each with an extension 1 arranged to lie in a plane a little to one side of the central longitudinal plane of the body of each of the two bolster sections, and when said sections are in place each extension thus offset occupies a position alongside of the extension on the opposed section. Along the upper margin of each extension 1 and for a part of its length each extension is provided with a flange 2 designed to reinforce that part. The sections A—B are further provided with nailling sill chairs as at 3 and 4, a seat 5 for the side sill member of the underframe, a side bearing 6, and a roping staple 7, which

also answers the purpose of a jacking casting. The overlapping extensions 1 of the bolster side sections are arranged to lie within the recess 8 of the spaced jaws 9 rising 5 from the center section C of the bolster, best known in the car art as the bolster center casting, which is provided with an integral center bearing portion 10. The jaws 9 are provided with holes 9^a which register with 10 the holes 1^a in extensions 1 through which are passed rivets or other fastening means 11. Such construction provides a rigid connection for the bolster parts, enabling the 15 assembled structure to act as a unit in resisting service stresses. To lend further rigidity to the engaging parts 1 and 9, the jaws 9 may be provided at their upper edges with outwardly projecting horizontal flanges 12 which terminate in vertical flanges 13 for 20 connecting the center sill 14 and flanges 15 of the side sections. To further insure the proper spacing of the opposed side sections when they are to be used in an underframe in which the center sills are continuous 25 through the bolster, as shown herein, they are each provided at their inner lower portions with shouldered recesses 16 adapted to receive the flanges 17 of the center section C, which flanges 17 assist in supporting the 30 complete bolster. Said flanges 17 are each provided with openings 18 which register with holes 19 of the side sections to receive fastening means, as rivets 20, for further securing said parts together. The central 35 section C is also provided with center pin socket 21 and an opening 22 to admit fastening means for securing the center pin in position.

The modified construction shown in Figs. 40 11 to 14, inclusive, differs from the preferred construction in that the central section C of the bolster instead of having a pair of upstanding jaws 9 embracing extensions 1 of the bolster side sections, is 45 provided with but a single vertical rib 23 centrally arranged upon said bolster section C and fitting between extensions 24 corresponding to the extensions 1 before indicated, but spaced apart to receive said rib 23 50 between them. The rib 23 terminates in oppositely extending connecting flanges 25 as shown in Fig. 13. The end flanges 26 and opposite flanges 25 are shortened to accommodate one of the bolster extensions 55 24, which lies in a plane above said flange 26 in the modification of Fig. 12.

Fig. 12 illustrates the relative positions of the engaging parts, and Fig. 14 shows the offset extensions 24 as located in the modification of Figs. 11 to 14, inclusive.

Shoulders 27 shown in Fig. 11 may be used with either the preferred or modified construction.

The invention is directed to the particular 65 manner of tying the assembled sections of

the bolster together and providing a central connection for them which may be within the center sill and connecting the lapping parts 1, 1 of the bolster sections A—B directly to a central member of the bolster, 70 which is shown as located between two spaced center sill members, but which, it is evident, may be combined with the extensions A—B and form a bolster without the said interposed sill members, if desired. In 75 other words, the bolster will be complete as a bolster if its side sections are carried into direct contact with the center section. In car underframes in which the center sill terminates between bolsters such an arrangement is desirable but is so evident from the disclosure that it is not specifically illustrated. This member C comprises a combined bolster filler casting and center bearing plate, which is adapted to be secured between and to the webs of the spaced center sills and to the lower flanges of the bolster sections A—B, or directly to the sections A—B if desired. Owing to the fact that the bolster center section is necessarily very 80 strong, there is a practical advantage in the connection of the extensions 1, 1 within and to an upward extension of said casting, as best shown in Fig. 5, though it is evident that the center bolster sections of Figs. 12, 85 13 and 14 may be substituted.

In the modification illustrated in Figs. 15, 16 and 17 a short cover plate is employed, said cover plate being riveted or otherwise secured directly to a top or horizontal flange 2, preferably formed integral with one of the extensions 1 before referred to, the other elements of the bolster being secured as hereinbefore described.

In Fig. 18 there is shown an additional 105 modification in which the flanges 2 and 12 are directly riveted by vertically disposed rivets.

In Fig. 19 the features of Figs. 15, 16, 17 and 18 are combined, there being shown the cover plate 28 of Figs. 15, 16 and 17 and the wide flange 2 of Fig. 18 and both secured by vertical rivets to wide outstanding flanges 12.

Owing to the fact that the bolster is composed of the principal elements comprising a central supporting section C and two side extensions A—B secured thereto, as shown, independently of the connection with center sills, it is obvious that the extensions 115 27 of the bolster sections A—B need not be employed, except to prevent shifting of the bolster with relation to the sills.

In assembling and disassembling the bolster parts the presence of center sills is not 125 material to the general design, as the parts (center and side) are then merely brought into more intimate contact if center sills are not to be interposed between the center and side bolster sections, and in either case 130

the central section C remains the principal supporting element for the bolster as a whole.

What I claim is:

5. 1. In a device of the character described, the combination of a sill, a bolster comprising a bolster center casting and side sections arranged on opposite sides of the sill and opposed to each other, and means integral with each of the bolster side sections lapping said bolster center casting and coöperating therewith for supporting the respective side sections.
15. 2. In a device of the character described, the combination of a sill, a bolster center casting, bolster side sections arranged on opposite sides of the sill and opposed to each other, and means integral with each of the bolster side sections and extending beyond one end of each of said sections lapping and being secured to said bolster center casting to support the respective side sections.
25. 3. In a device of the character described, the combination of a sill, a bolster central section provided with a center bearing portion and side sections arranged on opposite sides of the sill and opposed to each other, each of said side sections being provided with an integral extension projecting beyond one end thereof and adapted to connect directly to said bolster central section.
35. 4. In a device of the class described, the combination of a sill, a bolster comprising coöperating sections arranged on opposite sides of said sill, a bolster central section provided with a center bearing portion connected with said sill, and connected extensions on said side bolster sections secured directly to said bolster central section.
45. 5. In a device of the character described, the combination of a sill, a bolster comprising sections arranged on opposite sides of the sill and opposed to each other, and means integral with each of the bolster sections and extending beyond one end of each of the sections and passing through the sill and being directly connected together within the sill.
50. 6. In a device of the character described, the combination of a sill, a bolster comprising sections on two sides of the sill and lapping within the sill and a bolster central section secured directly to the lapping portions.
60. 7. In a device of the character described, the combination of a sill, a bolster comprising sections arranged on opposite sides of the sill and opposed to each other, each of said sections being provided with an integral extension projecting beyond one end thereof and adapted to lap and be directly connected within the sill to the other of said sections.
65. 8. In a device of the character described,

the combination of a sill provided with oppositely disposed laterally projecting flanges along one edge, a bolster comprising sections arranged on opposite sides of the sill and opposed to each other, each of said sections being provided with an integral extension projecting therefrom and adapted to project through the sill and lap the opposing section, and a bolster central section connected directly to said lapping portions.

9. In a device of the character described, the combination of a sill comprising spaced members, and a bolster comprising sections arranged on opposite sides of the sill and opposed to each other, one end of each of the sections abutting one of the sill members, said bolster sections being each provided with an integral portion extending beyond the end abutting the sill, said extending portions lapping and being directly connected between the spaced members of the sill.

10. In a device of the character described, the combination of a sill comprising spaced members, and a bolster comprising sections arranged on opposite sides of the sill and opposed to each other, one end of each of the sections abutting one of the sill members, said bolster sections being each provided with an integral portion projecting beyond the end abutting the sill and lapping the opposed section, and a bolster central section connected directly to each lapping member.

11. In a device of the character described, the combination of a sill comprising spaced members, a bolster comprising sections arranged on opposite sides of the sill and opposed to each other, one end of each of the sections abutting one of the sill members, said bolster sections being each provided with an integral portion projecting beyond the end abutting the sill and through the web of the sill, and a bolster central section provided with a seat for one of said shou- dered portions within the sill.

12. In a device of the character described, the combination of a sill comprising spaced members, and a bolster comprising side sections arranged on opposite sides of the sill and opposed to each other, one end of each of the bolster sections abutting one of the sill members, said bolster sections being each provided with an integral portion projecting beyond the end abutting the sill member, and a bolster central section provided with a pocket in which lapping portions of the bolster side extensions are held.

13. In a device of the character described, the combination of a sill comprising spaced members, and a bolster comprising side sections arranged on opposite sides of the sill and opposed to each other, one end of each of the bolster sections abutting one of the sill members, said bolster sections being each

provided with an integral portion projecting beyond the end abutting the sill member and being provided with a portion lapping the opposing portion between said sills, and 5 a bolster central section anchored to said lapping portions.

14. In a structure of the class described, the combination of spaced sills, a bolster having lapping portions between said sills, 10 and a central bolster section connected directly to said lapping portions.

15. As an article of manufacture, a bolster central section provided with a center pin socket and with a vertical extension adapted 15 to extend above said socket to lap and serve as an anchor for a plurality of lapping bolster parts adapted to be secured together by holding means extending through said lapping parts.

20. As an article of manufacture, a bolster central section provided with a pin socket and with sill attaching flanges and a seat for lapping complementary bolster elements.

25. 17. In a device of the character described, the combination of a sill, a bolster comprising center and side sections, the bolster side sections being arranged on opposite sides of the sill and opposed to each other, and means 30 integral with the side sections and co-operating with the center section for uniting the respective sections and maintaining said sections supported.

35. 18. In a device of the character described, the combination of a sill, a bolster comprising center and side sections, the bolster side sections being arranged on opposite sides of the sill and opposed to each other, and means integral with and extending beyond one end 40 of each of the side sections and engaging the center section to maintain said sections supported.

45. 19. In a device of the character described, the combination of a sill, a bolster comprising center and side sections, the side sections being arranged on opposite sides of the sill and opposed to each other, and means integral with and extending beyond one end of each of the side sections and adapted to connect directly with said center section.

50. 20. In a device of the character described, the combination of a sill, a bolster comprising center and side sections, the side sections being arranged on opposite sides of the sill and opposed to each other, and lapping extensions on said side sections secured directly to the center section.

55. 21. In a device of the character described, the combination of a sill, a bolster comprising center and side sections, said side sections being arranged on opposite sides of the sill and provided each with extensions lapping within the sill and directly connected to the center section.

60. 22. In a device of the character described,

the combination of a sill comprising spaced members, a bolster comprising center and side sections, said side sections being arranged on opposite sides of the sill and provided each with a flanged extension projecting through the respective sill members and adapted to overlap and engage the extension on the opposite side section. 70

23. In a device of the character described, the combination of a sill comprising spaced members, a bolster comprising a center section provided with a flanged extension, and side sections, said side sections being arranged on opposite sides of the sill and provided each with a flanged extension projecting through the respective sill member and adapted to overlap and engage the extensions on the other sections. 75

24. In a structure of the character described, the combination of a sill, a bolster comprising center and side sections provided each with a flanged extension adapted to overlap and engage the extensions on the respective sections within the sill. 80

25. In a car underframe, the combination 85 of a sill, a transversely extending supporting member comprising sections arranged on opposite sides of the sill and opposed to each other, and means integral with each of the sections and extending beyond one end of 90 each of the sections and passing through the sill and being directly connected together within the sill. 95

26. In a car underframe, the combination 95 of a sill, a transversely extending supporting member comprising sections on two sides of the sill, said sections having ends lapping within the sill, and tie members secured directly to the lapping portions. 100

27. In a car underframe, the combination 105 of a sill, a cross-bearing member comprising sections arranged on opposite sides of the sill and opposed to each other, each of said sections being provided with an integral extension projecting beyond one end thereof 110 and adapted to lap and be directly connected within the sill to the other of said sections. 115

28. In a device of the character described, the combination of a sill comprising spaced members, and a transverse supporting member comprising sections arranged on opposite sides of the sill and opposed to each other, one end of each of the sections abutting one of the sill members, said sections being each provided with an integral portion extending beyond the end abutting the sill, 120 said extending portions lapping and being directly connected between the space members of the sill. 125

29. In a device of the character described, the combination of a sill comprising spaced members, and a transverse member comprising sections arranged on opposite sides of the sill and opposed to each other, one end of each of the sections abutting one of the sill

members, said sections being each provided with an integral portion projecting beyond the end abutting the sill and lapping the opposed section, and an intermediate member connected directly to each lapping member.

30. In a device of the character described, the combination of a sill comprising spaced members, a transverse member comprising sections arranged on opposite sides of the sill and opposed to each other, one end of each of the sections abutting one of the sill members, said sections being each provided with an integral portion projecting beyond the end abutting the sill and through the web of the sill, and means for connecting said sections together and to the sill within the sill.

31. In a device of the character described, the combination of a sill comprising spaced members, and a transverse member comprising side sections arranged on opposite sides of the sill and opposed to each other, one end of each of the sections of the transverse member abutting one of the sill members, said sections being each provided with an integral portion projecting beyond the end abutting the sill member and lapping said projecting portion of the opposing section, and vertically disposed means connecting said sections to said sill.

32. In a car underframe, the combination of a sill comprising spaced members, and a

transverse member comprising side sections arranged on opposite sides of the sill and opposed to each other, one end of each of the sections abutting one of the sill members, said sections being each provided with an integral portion projecting beyond the portion abutting the sill member and through the sill, and each said portion lapping the opposing portion between said sills, and means intermediate the sills anchoring said lapping portions.

33. In a car underframe, the combination of a sill, a transverse member comprising center and side sections, the side sections being arranged on opposite sides of the sill and opposed to each other, and the center sections extending beyond one end of each of the side sections and adapted to be connected directly together within and entirely below the top of the sill.

34. In a car underframe, spaced center sills with vertically disposed perforated webs, separately formed transverse load supporting members projecting through said sill from opposite sides and means for uniting said sills and transverse members intermediate said sills.

In witness whereof I have hereunto set my hand in the presence of two witnesses.

KARL M. HAMILTON.
